US00D887819S

(12) **United States Design Patent** (10) **Patent No.:** **US D887,819 S**
Smith et al. (45) **Date of Patent:** **** Jun. 23, 2020**

(54) **LIGHTED WALL PLATE**

- (71) Applicant: **SnapRays LLC**, Provo, UT (US)
(72) Inventors: **Jeremy C. Smith**, Orem, UT (US);
Phillip W. Dietz, St. George, UT (US);
Martin Johnson, Draper, TN (US)
(73) Assignee: **SnapRays LLC**, Vineyard, UT (US)
(***) Term: **15 Years**
(21) Appl. No.: **29/629,812**
(22) Filed: **Dec. 15, 2017**

Related U.S. Application Data

- (63) Continuation of application No. 29/598,255, filed on Mar. 23, 2017, now Pat. No. Des. 819,426, which is a continuation of application No. 15/145,749, filed on May 3, 2016, now Pat. No. 9,787,025, which is a continuation-in-part of application No. 14/549,143, filed on Nov. 20, 2014, now Pat. No. 9,362,728, which is a continuation-in-part of application No. (Continued)

(57) **CLAIM**

The ornamental design for a lighted wall plate, as shown and described.

DESCRIPTION

FIG. 1 is a perspective view of a lighted wall plate in accordance with my new design;

FIG. 2 is a front view thereof;

FIG. 3 is a top view thereof;

FIG. 4 is a bottom view thereof;

FIG. 5 is a left side view thereof; and,

FIG. 6 is a right view thereof.

The broken lines represent unclaimed subject matter and form no part of the claimed design. The back of the lighted wall plate is not visible during use and forms no part of the claimed design.

1 Claim, 2 Drawing Sheets
